UNITED STATES PATENT OFFICE.

LEON C. SCHWAB, OF MILWAUKEE, WISCONSIN, ASSIGNOR TO A. O. SMITH COMPANY,
OF MILWAUKEE, WISCONSIN, A CORPORATION OF WISCONSIN.

DESIGN FOR AN AUTOMOBILE-WHEEL.

47,390.

Specification for Design.

Patented May 25, 1915.

Application filed March 9, 1914. Serial No. 823,592. Term of patent 14 years.

To all whom it may concern:

Be it known that I, LEON C. SCHWAB, a citizen of the United States, residing in Milwaukee, in the county of Milwaukee and State of Wisconsin, have invented a new, original, and ornamental Design for an Automobile-Wheel, of which the following is a specification, reference being had to the accompanying drawing, forming a part thereof.

The figure is a perspective view of an automobile wheel showing my new design.

I claim:

The ornamental design for an automobile wheel as shown.

LEON C. SCHWAB.
